Inventor

Augustin Fernandez
By his Attorney
Edgarworth Greene

UNITED STATES PATENT OFFICE.

AUGUSTIN FERNÁNDEZ, OF NEW YORK, N. Y., ASSIGNOR OF ONE-HALF TO CHARLES M. CONLON, OF NEW YORK, N. Y.

ELECTRICAL FUSE.

Application filed September 4, 1926. Serial No. 133,667.

This invention relates to fuses used in electrical circuits and more particularly to what may be termed socket fuses; and the object of the invention is to provide a fuse mounted 5 in a suitable holder, having the proper terminal contacts, to form an independent unit adapted to enter an ordinary socket just above a lamp or plug, and as the latter is screwed up into position, form an electrical 10 connection with the fuse element in circuit, means being provided to position the holder on the plug to prevent it from slipping off and thereby facilitate its use. Other objects 15 will appear throughout the following detailed description.

The use of a device of this character has many advantages, particularly in manufacturing plants where numerous machines are being operated from a common source of 20 power coming over one line or circuit which is protected by only the usual fuse mounted in a fuse box. Should this fuse blow, all the machines on the circuit must of necessity come to a stop until such time as the trouble 25 may be located and a new fuse reinstalled.

Meanwhile the work is held up on all of the machines, but with my improved fuse in use in every socket any trouble arising can be immediately localized and only the disabled machine is made idle until such time as the difficulty may be corrected and the blown fuse replaced.

My invention is fully set forth in detail in the following specification and drawings 35 forming a part thereof in which latter I have illustrated a preferred embodiment of my invention.

Referring to such drawings,

Figure 1 is a vertical section of my improved fuse shown operatively positioned intermediate the socket terminals and an electrical element to be inserted in the socket, the two latter being indicated in dotted lines.

Figure 2 is a top plan view of the fuse.

Figure 3 is a bottom plan view of same.

Figure 4 is a sectional view taken on the line 4—4 of Figure 2.

Figures 5 and 6 are top and bottom plan views respectively of the fuse holder.

Figure 7 is a plan view of one of the insulators or mica disks used in the fuse.

Figure 8 is a plan view of the index card.

Figure 9 is a perspective view of one of 55 the contacts.

Figure 10 is a sectional view of a modified form of the invention.

The holder 10 comprising a casing, is preferably made of porcelain, but other suitable insulating material may be used. It is cylindrical and as shown in Figure 1 in section, resembles a letter H, having an upper and lower extending flange 11 and 12 respectively. These flanges constitute positioning means so that the fuse may be placed upon 60 a plug or lamp base indicated at 13 in dotted lines, the boss 14 entering the recess within the annular walls of the flange to effectively prevent the fuse from slipping off of the plug prior to screwing the latter into the socket. 65 While the lower flange is shown somewhat longer than the upper one, both could be made of equal length if desired and the parts could then be assembled in an opposite order within the holder. 70

The flanges serve also as a protective housing and provide a convenient form of unit for packing and shipping purposes. Contact pieces 15 and 16 are adapted to fit within depressions 10^a and 10^b in the bridge 80 17 of the holder, bosses 18 and 19 passing through openings in the contact pieces. A mica disk 20, about $\frac{3}{32}$ " thick, is mounted over the contact 15, the former being provided with an aperture 21 so that the terminal 15' of the contact can be first passed through the aperture after which it is given a right angle bend as shown. A mica disk 22, about $\frac{1}{2}$ " thick, is placed over the contact 16 and has a similar aperture 23, and over this is placed a paper disk 24 comprising an index card and apertured at 25. Then another mica disk 26 is positioned over the disk 24 and has an aperture 27. Through 90 these apertures the terminal 16' of the contact 16 is passed and bent over in a manner similar to the other contact. 95

Rivets 28 are then passed through holes 29 in the several disks as well as holes 30 in the bridge 17 and serve effectively to bind 100 the parts together in assembled relation. The index card may have suitable legends printed on its lower surface, such for example as amperes and volts, thereby designating the character of the fuse, and which 105 will be clearly visible through the mica disk over it. An aperture 31 in the bridge of the holder permits the fuse wire 32 to be connected to the two contacts to which it is soldered. The index card is provided with 110

a peep hole 33 to visually detect the condition of the fuse wire 32.

In Figure 9 one of the contacts is shown with its terminal prior to bending so that the several disks can be readily slipped over it, and when in proper assembled position the terminal can be pressed down and the rivets put in with one operation. Obviously one of the contacts will be soldered to one end of the fuse wire before assembly subsequently followed by the soldering of the other end after assembly.

In the modification shown in Figure 10 no rivets are used, the inner walls of the flanges being undercut at 34 so that the disks can be snapped into place and thereby so retained.

As various modifications within the scope of the appended claims may be made without departing from the spirit of my invention, such changes in details of construction which are merely matters of form of design are to be considered within the scope of the invention.

I claim:

1. A socket fuse adapted to be interposed between the contact terminals of a socket and an electrical element inserted therein comprising a holder, a fuse wire operatively mounted in said holder, the end of said holder being recessed to receive one of said contact terminals and to provide supporting means circumferentially disposed around said recess to thereby sustain said holder on said electrical element prior to the aforesaid assembled relation.

2. A socket fuse comprising a holder of

tubular configuration, and provided with a substantially centrally disposed transverse wall, to thereby form recesses above and beneath same, contacts mounted on opposite sides of said wall within said recesses, a fuse wire extending through said wall and connected to said contacts, and heat insulating means extending over the ends of said fuse wire.

3. A socket fuse comprising a holder of tubular configuration, and provided with a substantially centrally disposed transverse wall, to thereby form recesses above and beneath same, contacts mounted within said recesses in locking engagement with said wall and on opposite sides thereof, a fuse wire extending through said wall and connected to said contacts, and heat insulating means extending over the ends of said fuse wire.

4. A socket fuse comprising a holder of tubular configuration, and provided with a substantially centrally disposed transverse wall, to thereby form recesses above and beneath same, contacts mounted within said recesses on opposite sides of said wall, a fuse wire extending through said wall and connected to said contacts, and heat insulating means extending over the ends of said fuse wire, and including an index card provided with an inspection aperture.

5. A socket fuse comprising a holder, contacts mounted at opposite ends thereof, a fuse wire connecting said contacts, heat insulating means extending over the ends of said fuse wire, and including an index card.

AUGUSTIN FERNÁNDEZ.
